JAMES W. COLE, OF WESTFIELD, MASSACHUSETTS, ASSIGNOR OF TWO-THIRDS
TO GEORGE T. MOORE AND CYPRIAN J. KING, BOTH OF SAME PLACE.

DRAW-BAR FOR CARS.

SPECIFICATION forming part of Letters Patent No. 338,829, dated March 30, 1886.

Application filed July 20, 1885. Serial No. 172,069. (No model.)

To all whom it may concern:

Be it known that I, JAMES W. COLE, a citizen of the United States, residing at Westfield, in the county of Hampden and State of Massachusetts, have invented new and useful Improvements in Draw-Bars for Cars, of which the following is a specification.

This invention relates to continuous draw-bars for railway-cars, so constructed as to form a continuous draw-bar from one end of the car to the other, and to form also a buffer for either end of the car.

The construction of my improvement is fully shown in the accompanying drawings, forming part of this specification, in which—

Figure 1 is a plan view of the bottom of the car, and Fig. 2 is a perspective view of my devices and portions of the car-timbers turned bottom side up, showing more clearly the construction of the operating parts at one end of the car.

The parts are constructed in precisely the same manner at both ends of the car.

In the drawings, A is the bottom of the car, and B the two central longitudinal timbers, between which my draw-bars are placed.

E E are the draw-bars proper, and b b are the connecting-rods uniting the devices of both ends of the car.

a a are spiral springs on the ends of connecting-rods b, and S S are spiral springs on the shank d of the draw-bar.

D D are the notched supports for the cross-heads c c' c'.

m m are keys through shank d.

The supports D, supporting cross-heads c c' c' are bolted securely to the central longitudinal timbers, B, of the car, and are notched to receive the ends of the cross-heads, as shown, in such a manner as to allow of limited longitudinal movement of the said cross-heads in either direction between timbers B. The spring S always keeps the cross-head c' back in its notch as far as it can go. The shank d of the draw-bar E passes through cross-heads c c' c' and keys m are inserted through the said shank back of and in contact with said cross-heads c' and c'. A spiral spring, S, is placed on that portion of shank

d between cross-heads c' and c'', abutting on each of said cross-heads. The connecting-rods b b pass through the cross-heads c' c'' at either end of the car nearly to cross-heads c' c'', and on the ends of the rods b thus projecting through cross-heads c' c'' are placed the spiral springs a a, said springs abutting on cross-head c'' and against a nut screwed on the end of said rod d. Thus connected, the rods d, together with draw-bars E, with their shanks d, form a continuous and co-operatively-acting draw-bar and buffer for each end of the car.

The plates P are secured to the notched cross-head supports by bolts, so that they can easily be removed by removing the nuts.

In practice, when the draw-bar E is driven in toward the car—as in coupling one car to another, for instance—the shoulder on the draw-bar, just in front of cross-head c, abuts on said cross-head and forces it in backward in the notch in support D, compressing spring S, which thus acts as a buffer-spring. When the train is started ahead, the cross-bars c' and c'' are all drawn forward in the direction the train is moving, compressing the springs on both ends of both of the connecting-rods between the cross-heads c' and the nuts on the ends of said rods. Thus it will be seen that all shocks and sudden strains on the draw-bar are obviated, either when one draw-bar is driven in, as in coupling, or when both are driven inward at the same time, as in the sudden stoppage of a train, or when both are drawn outward, as in the starting of a train.

What I claim as my invention is—

1. Two sets of draw-bar connections for a car, one at each end thereof, each consisting of a draw-bar, E, having a rigid shank, b, thereon, extending through three cross-heads, c' c'' c', and having an engagement with the rear side of two thereof, a spring, S, located on the shank of the draw-bar between the cross-heads c' c', two longitudinal notched supports, D D, for the ends of said cross-heads, in which the latter have a limited movement imparted thereto by either draw-bar, two connecting-rods b b, whose ends pass through the cross-head c' of each set of said connections,

and a spring, a , between the end of each of said rods and the side of said cross-head c^2 , all combined and operating substantially as set forth.

5 2. The parallel separated timbers $B B$, secured to the bottom of the car, the notched supports $D D$, secured to the opposite inner sides of said timbers at each end of the car, the cross-heads $c' c^2$, engaging in the notches in said supports, and having a limited movement therein, the draw-bars $E E$, each having a shank passing through said cross-heads

and having an engagement with the two inner ones, the springs $S S$, one on each draw-bar shank between the cross-heads $c' c^2$, the connecting-rods $b b$, extending through the cross-head c^2 at each end of the car, and each having thereon, between its end and the side of said cross-heads c^2 , the spring a , combined and operating substantially as set forth.

15 JAMES W. COLE.
